Benjamin Lapham, Waterford &c. U. S.

Letters Patent.

The Schedule referred to in these Letters Patent, and making part of the same, containing a description in the words of the said Mr. Benjamin Lapham, himself of his Improvement in the power loom,

To all persons to whom these presents shall come: Be it known or that I Benjamin Lapham, of Waterford in the County of Lataugau State of New York, have invented a new and useful improvement in the common power loom, a full and accurate description of which is as follows. The object of this improvement is to wind or let off the warp from the warp roll in the exact ratio in which the cloth is made by the operation of reeling thereby avoiding those imperfections which are caused by rendering off the warp under tension which causes the web to be much more even and uniform in texture than that heretofore generally woven by the power loom or the hand loom. On the end of the warp roll or main beam is a wheel about half the diameter of the said warp roll, more or less, on which wheel are shawls corresponding with the teeth of a worm or ratchet wheel which runs on the back end of a main or driving shaft descending forward in an angle of perhaps twenty five or thirty degrees with the horizon and passing thus forward and downward to stand on the middle side rail of the loom which stand or stand is at right angles with the axis of the worm wheel; and is a little back of the main or driving shaft of the loom. At the forward end of this stand is a catchet wheel, which is fed by a hand standing nearly in a vertical position, and operating as it rises, on the ratchet wheel at about the middle of its horizontal diameter. This hand is kept on the teeth of the ratchet by a spiral spring, extending backwards and fastened to the frame of the loom at a position somewhat elevated as at the same to keep the hand from descending except when forced down as will be seen after described. The hand is raised to produce its action on the catchet, by an elbow the angle of which turns on the same pivot which secures the above mentioned

stand

above mentioned stick to the side rail of the loom; and a rod attached by the forward end to the sword of the batten, and by the rear back end to the lower branch of this elbow, which the anterior of the upper branch of said elbow is attached by a movable joint, to the lower end of the said hand. It follows of course that as often as the batten goes back, the hand of the ratchet will be raised by the backward motion of the sword, which if it have descended low enough to take one or more new notches in the ratchet, the ratchet will be turned one or so many notches forward, and the worm screw will turn with it and render off the warp accordingly. But if this ratchet should pass one or more notches at every motion of the batten, it would probably render off the warp too fast, and make the batten too thin. On the other hand if it should not operate at all, as the cloth prepared back against the reed, the action of the loom would cease. This operation I adjust I calculate in the following manner, In front of the back roller I place another a little above the other, which forward roller rests at the ends, on the forward ends of two levers, the back ends of which are held down by special springs attached to the frame below. From the forward end of one of these levers projects a small rod downward to that branch of the above described lever, to which the ratchet hand is attached which has passes through a hole in said branch and having a shoulder against the upper surface, pushes it down as often as the rod and lever to which it is attached are forced down by the increase and tension of the warp, and the different connections of the said apparatus for operating the hand are so constructed as to give the hand the necessary play. By these means as the warp grows tight by the accumulation of the cloth, its tension exceeds the roller to descend, and the ratchet takes one or more new notches on the warp is rendered off accordingly; and if no cloth is woven by the action of the loom the warp remains loose and the hand not descending, the warp remains stationary. I have claim

To the use of the wheel and worm device, not to the hand and ratchet in rendering the warp from the warp to the yarn beam, but to the principle of feeding the ratchet by means of the increased tension of the warp, and this claim is without any limitation, and I also claim in the entire combination, in which is herein described when taken collectively but not separately except as above stated.

I, witness that the foregoing is a true and accurate description of my said improvement, I have hereunto set my hand in Waterford aforesaid on the sixteenth day of day in the year one thousand eight hundred and thirty six.
